Fig. 3

Fig. 4

Fig. 5

Fig. 6

Fig. 7

Fig. 8

FIG. 1 is a front perspective view of a pressure regulator or similar article showing our new design,

FIG. 2 is a rear perspective view thereof,

FIG. 3 is a top plan view thereof on a reduced scale,

FIG. 4 is a side elevational view thereof on a reduced scale,

FIG. 5 is a front elevational view thereof on a reduced scale,

FIG. 6 is a side elevational view thereof on a reduced scale,

FIG. 7 is a bottom plan view thereof on a reduced scale, and

FIG. 8 is a rear elevational view thereof on a reduced scale.

We claim:

The ornamental design for a pressure regulator or similar article, substantially as shown and described.
